(57) **CLAIM**

The ornamental design for a transport holder for cylindrical tanks, as shown and described.

DESCRIPTION

FIG. 1 is a front perspective view of a transport holder for cylindrical tanks showing my new design;
FIG. 2 is a front elevational view thereof, the back elevational view being identical;
FIG. 3 is a top plan view thereof;
FIG. 4 is a bottom plan view thereof; and,
FIG. 5 is a right side elevational view thereof, the left side elevational view being identical thereto.

1 Claim, 3 Drawing Sheets

FIG. 2

FIG. 3

FIG. 4

FIG. 5
